UNITED STATES PATENT OFFICE.

ASYA ABRAMOVICH, OF NEW YORK, N. Y.

CHILD'S GARMENT.

Application filed September 28, 1926. Serial No. 137,385.

My invention relates to children's or infants' garments and has a particular reference to washable breech-cloths or diapers.

The object of my invention is to provide such a garment for covering the child's body in place of a commonly used square piece of cloth secured in a proper position by means of safety pins.

In view of the fact that the use of safety pins is dangerous and also inconvenient, I provide a garment with convenient means for holding it in place. My invention is more fully described in the accompanying specification and drawing in which—

15 Fig. 1 is a plan view of my garment in an unfolded position, Fig. 2 is an end view, Fig. 3 is the same garment when folded for use, Fig. 4 is a view of the garment finally folded and buttoned, Fig. 5 is an enlarged 20 sectional view of the edge of the garment with a female portion of a snap fastener, Fig. 6 is the same with the male portion of a fastener, Fig. 7 is an elevation of a buckle with buttons, attached to a belt in 25 a modified form of this garment, and Fig. 8 is an end view of the buckle.

My garment consists of a rectangular piece of cloth 1 one end of which is folded on itself three times forming quadruple 30 thickness of cloth 2. The remaining portion of the cloth forms a square. The portion 2 forms a belt for the garment. It is provided with two sets of snap fasteners on the ends: male fasteners 3 and female 4. The 35 latter are made with enlarged heads 5 (Fig. 5). In addition to the fasteners the belt portion 2 is provided with holes or slits 6 for a ribbon or belt 7. In the center of the square 1 a ribbon or tape loop 8 is attached.

40 When it is desired to use the garment it is first folded diagonally across the line 9—9, then it is folded across the line 10—10. Fig. 3 shows the garment in such folded position. The cloth is folded on the same 45 side with the folds of the belt portion 2. This insures a uniform thickness of four layers of cloth beginning with the belt portion 2 and in the triangle Fig. 3.

The garment is then placed on the child's 50 body and the belt portion secured with the

snap fasteners as shown in Fig. 4 (the child's waist is indicated with dotted lines 11). The apex of the triangle of the folded cloth is brought from the rear around the crotch and is fastened in this position by placing the loop 8 around the buttons 5. In this manner the garment provides openings for the child's legs (indicated with dotted lines 12 in Fig. 4).

It is possible to use a single button 5, but two buttons as shown give more secure fastening and, besides, the loop 8 is held tighter with two buttons than with one.

The ends of the ribbon 7 may be then tied together as shown in Fig. 9, thereby holding the garment more securely, tightening it on the child's body and giving a neater appearance.

Instead of the snap fasteners ordinary buttons may be sewed on on one side of the belt 70 portion 2 with buttonholes on the other side. The buttons may be also placed on the belt buckle 13 (Fig. 7) to which one end of a belt 14 is attached. The buttons 15 are attached to the front surface of the buckle and 75 serve only to hold the loop 8.

Important advantages of my garment are that it can be easily and quickly fastened on the child's body, is neat in appearance and eliminates the use of safety pins. 80

I claim as my invention:

In a child's garment, the combination with a substantially rectangular piece of cloth, one side of said cloth being folded three times in a narrow strip forming a belt portion, the remaining portion of said cloth being cut in the form of square and folded twice from side to side thereby forming a triangle of the same thickness as said belt portion, snap fasteners with projecting heads on said garment adapted to connect the ends of said belt portion, and a tape loop attached to the apex of said triangle and adapted to engage said snap fasteners' heads when said garment is in use. 85 90 95
